The ornamental design for a control device, as shown.

DESCRIPTION

FIG. 1 is an upper-right-front perspective view of a first embodiment of a control device showing the new design. FIG. 2 is a lower-left-front perspective view of the first embodiment.

FIG. 3 is a lower-right-rear perspective view thereof.

FIG. 4 is a front elevational view thereof.

FIG. 5 is a rear elevational view thereof.

FIG. 6 is a left side elevational view thereof.

FIG. 7 is a right side elevational view thereof.

FIG. 8 is a top plan view thereof.

FIG. 9 is a top bottom view thereof.

FIG. 10 is an upper-right-front perspective view of a second embodiment of the control device showing the new design.

FIG. 11 is a lower-left-front perspective view of the second embodiment.

FIG. 12 is a lower-right-rear perspective view thereof.

FIG. 13 is a front elevational view thereof.

FIG. 14 is a rear elevational view thereof.

FIG. 15 is a left side elevational view thereof.

FIG. 16 is a right side elevational view thereof.

FIG. 17 is a top plan view thereof; and,
